UNITED STATES PATENT OFFICE.

EMERY D. WATERBURY, OF DENVER, ASSIGNOR OF TWO-THIRDS TO STEPHEN W. KEENE, OF ASPEN, AND SILAS E. HOSKINS, OF DENVER, COLORADO.

BILLIARD-TALLY.

SPECIFICATION forming part of Letters Patent No. 388,006, dated August 14, 1888.

Application filed February 16, 1888. Serial No. 264,206. (No model.)

To all whom it may concern:

Be it known that I, EMERY D. WATERBURY, a citizen of the United States of America, residing at Denver, in the county of Arapahoe and State of Colorado, have invented certain new and useful Improvements in Billiard-Tallies: and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to certain new and useful improvements in billiard tallies or counters; and it consists in the novel construction and arrangement of the parts, which will be more fully hereinafter described, and pointed out in the claims.

The object of my invention is to facilitate the keeping of the tally of a game of billiards, both as to the number of games played and the points made during the same, the parts of 25 the device being simple and effective in their construction and operation, strong and durable, easily handled and readily understood, and cheap in manufacture. I attain this object by the construction illustrated in the accompanying drawings, wherein like letters of 30 reference indicate similar parts in the several views, and in which—

Figure 1 is a sectional elevation of my improved device shown mounted in an operative position. Fig. 2 is a rear elevation of the register. Fig. 3 is a transverse vertical section of the said register.

A A' indicate hollow depending brackets or hangers, which have enlarged hollow T-heads 40 a a' secured to their lower ends. Secured to the inner opposingly situated horizontal T-heads a a' is a pipe or tube, B, upon which the point-counters B' are mounted. A small rod, C, is mounted within this tube B, which has a gravity-pawl, c, mounted in the lower portion 45 thereof, which plays through a slot, b', formed in the lower right-hand portion of the tube B. The said rod C, adjacent to its inner end, has a depending stud or pin, b, therein, which also 50 plays in the slot b'. The inner end of the rod C is formed with an eye, to which the cord D

is secured at one end, and, extending through the tube, passes over a sheave or pulley, d, mounted in the T-connection a on the lower end of the bracket or hanger A. The said cord 55 D, extending down from said T-connection, is provided with a handle on the lower end thereof, which is designed to be within reach of one of the players or a game-keeper. The opposite end of the rod C is also formed with an eye, and has a cord, E, secured thereto, which passes through the tube B and over a sheave or pulley, e, mounted in the T-connection a' on the lower end of the bracket or hanger A', and then passes up through said bracket A' 60 and over a pulley, e', mounted in a hanger, e'', and over a pulley, e'', which is mounted in a hanger, e', and then down and is secured to the upper end of a retractile spring, S', which is connected to a lever-arm, F', of the register, 65 a like spring, S'', being also secured to the said arm F' of the register and opposingly situated to the aforesaid spring S'.

Within the tube B an elongated coiled spring, S, is mounted, which is secured at one end to the rod C and at its opposite end within said tube B. Surrounding the central portion of the said tube B is a stop-collar, B'', against which the pin b on the rod C is adapted to have bearing and limit the movement of the 70 said rod in the direction of the arrow against the action of the spring S.

The operation of the mechanism thus far described is as follows: When a point is made by one of the players, one of the counters is 75 pushed along the tube B in the direction of the arrow and passes the depending gravity-pawl c, secured to the rod C. This gravity-pawl c is constructed with an oblique side adjacent to the counters, as shown in Fig. 1, which permits of the counters riding thereover; but when said counters get beyond the said pawl they are prevented from being accidentally shoved backward by the said pawl c, which bears against the shoulder c', formed in the rod C, 80 adjacent to the pivotal pin of the pawl c, as fully shown. The pawl, when raised by one of the counters passing thereover, is pressed upward into the recess formed in the lower portion of said rod C. The counters B' will have 85 bearing against the pin or stud b, and when the tally of points shall have been completed 90

in the game the cord D is drawn downward, which draws the rod C toward the T-connection *a* on the lower end of the bracket A, thus pressing the pawl upward into the groove in 5 rod C, the stud or pin *b* forcing the counters B' into the position shown to the right in Fig. 1. The cord D is then released, when the rod C will return to its normal position and the parts be in position for the beginning of a new 10 game. When the rod C is drawn toward the right by the cord D, it of necessity pulls the cord E, which acts through its connections on the springs S', which draws the arm F³ of the register F upward against the action of the 15 opposingly-situated spring S³, which afterward returns the said arm F³ to its normal position.

The construction of the register is as follows: The operative mechanism is mounted in 20 a ring or case, F, provided at front with a fixed dial, f², and at rear with a bridge-piece, f³, provided centrally with a bearing, in which is journaled a hub, W', in the forward end of which is bored a socket to receive the rear 25 end of a spindle, W, the forward end of which passes through a central aperture in the dial f², and is provided with an indicator-hand, f'. On the forward end of the hub W' is secured a lever, F³, and a ratchet-wheel, W², a grooved 30 pulley, w², being rigidly secured to the spindle W to occupy a position between said ratchet-wheel and the register-dial, as shown. The case F is provided at one side with a recess, F², within the lower end of which is pivoted 35 a pawl, P, arranged to engage the teeth of the ratchet-wheel W², said pawl being held up to its work by a spring, p, secured about midway of the length of the recess F² by a stud or screw, p², which also serves as the bottom stop or rest for the lever F³. This lever 40 F³ is provided with a spring pressed pawl, P', also arranged to engage the teeth of the ratchet-wheel W², and is at its outer end connected to coiled springs S' and S³, the 45 spring S' being secured to the depending pull-cord E of the tally and the spring S³ to a fixed point. The upper wall of the recess F² is at such distance from the screw p² as to arrest the movement of the lever F³ when it has 50 moved a sufficient distance upward to advance the ratchet-wheel W² one tooth with respect to the pawl P, the latter being designed to prevent a retrograde movement of the wheel upon the backward movement of the lever F³. The 55 notches or teeth of the ratchet-wheel W² are spaced to accord with the figures or marks on the dial, in order that when the ratchet-wheel is advanced one tooth the hand or indicator f' will be moved from one figure or mark to the 60 next, and so on, the friction between the spindle and socket and between the adjacent faces of the wheel W² and pulley w² being sufficient to insure a corresponding forward movement of the wheel and hand, and this movement 65 causing the pull-cord f to be wound upon the pulley w². To attain a greater friction be-

tween the ratchet-wheel and the pulley w², I interpose a coiled spring, S², between the bridge f³ and the back of the wheel, as shown in Fig. 3.

In operation the counters B will be pushed forward to mark the progress of the game, and upon its completion the cord D will be pulled to restore the counters to position for counting another game. Motion will meanwhile be transmitted through cord E and spring S' to lever F³, lifting the latter to move the hand or indicator f' forward one score. As, however, the counters in being returned must move a greater distance than the end of lever F³ in advancing the wheel W² one tooth, I interpose between the cord E and the lever spring S', which permits of the movement of the cord after the lever has been stopped by contact with the upper end or wall of the recess F². Upon the release of the cord D the springs S' and S will restore the parts to their normal positions.

Upon the completion of a series of games which have been marked by the register the cord f is drawn down, this action resulting in rotating the pulley w², and the spindle W and hand f', which are connected thereto, backward until the hand is stopped by contact with the pin f', projecting from the face of the dial in line with the zero-point marked thereon, the wheel W², lever F³, and hub W' being meanwhile held at rest by the engagement of the pawl P with one of the notches in wheel W².

I claim—

1. The combination of the tubular hangers or brackets having hollow T-connections on their lower ends, in which the two ends of a tube are secured, the sliding rod within said tube having a gravity pawl or pin working in a slot in the lower portion thereof, the pull-cord connected to one end of said sliding rod, and the cord and spring secured to the opposite end of said rod and in connection with a register, substantially as described.

2. The combination, with the tubular hangers having hollow T-connections on their lower ends to support a tube, B, of a sliding rod, C, having a gravity-pawl, a lower depending pin working within a slot within said tube, and central collar, B², a pull-cord connected to one end of said rod, the resisting-spring connected to the opposite end, and the cord E, also connected to the opposite end of the rod C at one end, and at its opposite end in connection with and operating a register, substantially as described.

3. The combination, with the tube B, supported as set forth, of the rod C, moving therein, having the gravity-pawl and stop-pin playing in the slot in said tube, and the connections with said rod, substantially as and for the purpose set forth.

4. The combination, with the tube B, supported as set forth, of the rod C, moving therein and having the connections, and retractile spring, as set forth, provided with a

gravity-pawl which prevents the backward return of the counters after passing thereover, substantially as described.

5. The combination, with the tube B, supported as set forth, and carrying the counters, of the rod C, having the connections, as set forth, and a stud or pin, b, playing in a slot in the said tube B and adapted to force the counters back to their normal position, substantially 10 as described.

6. The combination, with the tube B, supported as set forth, adapted to have the point-counters mounted thereon, of the rod C, having the connections, as set forth, and the stud 15 or pin b, playing in the slot in the lower portion of said tube for the purpose of returning the point-counters to their normal position, and a collar, B', surrounding the tube B, against which said stud or pin b engages, for the purpose 20 set forth.

7. The combination, with the tube B, supported as set forth, of the rod C, having the stud b and gravity-pawl c, a pull-cord, D, connected to one end of said rod, a retractile 25 spring, S, secured to the opposite end thereof, and a cord, E, secured to the opposite side of the said rod C, the springs S' and S'', and the arm or lever F' of the register, substantially as described.

30 8. The combination, with the tube B, a rod, C, therein and its connections, as set forth, of the springs S' and S'', the arm or lever F' of the recorder, the ratchet-wheel W' and its hub, the dial-plate, the spindle W, and the hand f', secured thereto, substantially as described.

9. The combination, with the point-counting mechanism, of a game-register consisting of a dial, a hub mounted in rear of the dial and carrying a ratchet-wheel, an actuating-lever 40 fulcrumed on the hub and carrying a pawl to engage the teeth of the ratchet-wheel, a spindle connected frictionally with the ratchet-wheel and protruding beyond the dial, and a hand carried by said spindle, substantially as described.

45 10. In a register, in connection with the

point-tally, as set forth, the arm F', the block or supporting-piece W', having the shoulder, as set forth, the spindle W, the spring S', the ratchet-wheel W', the pawls P and P', having the springs p and p', arranged as set forth, the pulley w', the dial-plate f', the hand or indicator f', and the pull-cord f, connected to the pulley w', substantially as described.

11. In a billiard-counter, the combination 55 of the tube, supported as set forth, having the point-counters marked thereon, of a rod within said tube having mechanism in connection therewith for returning the point-counters to their normal position and preventing their return when once adjusted, the said rod having suitable connections with a game-register, substantially as described.

12. In a billiard-counter, a tube supported as set forth, having a rod therein relatively 65 acting with the point-counters upon said tube, and having an operating pull-cord and a cord in connection with the game-register, substantially as described.

13. The combination, substantially as before 70 set forth, of the point-counters mounted to slide on a slotted tubular support, the rod mounted to slide in said support and provided with a fixed pin, pull-cords D and E, connected to the ends of said rod, a game-register 75 provided with an actuating-lever, and a spring interposed between cord E and said lever.

14. The combination, with a tube carrying point-counters, of a rod therein, constructed as set forth and having cord-connections, as described, a spring, S, secured to said rod, and the springs S' and S'', secured to the lever-arm of a game-register in connection with one of the cords attached to the said rod, substantially as described.

8 In testimony whereof I affix my signature in presence of two witnesses.
